UNITED STATES PATENT OFFICE.

CONRAD V. O'MALLEY, OF ROME, NEW YORK.

NON-REFILLABLE BOTTLE.

1,127,497.

Specification of Letters Patent.

Patented Feb. 9, 1915.

Application filed November 29, 1913. Serial No. 803,802.

To all whom it may concern:

Be it known that I, CONRAD V. O'MALLEY, a citizen of the United States, residing at Rome, in the county of Oneida and State of 5 New York, have invented new and useful Improvements in Non-Refillable Bottles, of which the following is a specification.

The invention relates to bottles of the non-refillable type, and has for an object to provide a bottle which, when the original contents have once been withdrawn therefrom, cannot be conveniently refilled with a spurious fluid and sold upon the market as the genuine article.

15 The invention comprehends, among other features, the provision of a bottle which, when the original contents are withdrawn therefrom, must be partially destroyed and which, when partially destroyed as mentioned, cannot be conveniently filled with a spurious fluid and rebuilt to have the appearance of the original bottle, thus preventing spurious dealers from using the bottle for selling spurious fluids under the name 25 of the original manufacturer and as the original contents of the bottle.

In the further disclosure of the invention reference is to be had to the accompanying drawings, constituting a part of this specification, in which similar characters of reference denote corresponding parts in all the views, and in which:

Figure 1 is a vertical sectional view taken through the neck of the bottle; Fig. 2 is a 35 fragmentary vertical sectional view of the bottle, showing the frangible portion removed; and Fig. 3 is a perspective view of the baffle member.

Referring more particularly to the views, 40 I disclose a bottle body 10 including a main integral neck 11 adapted to receive therein a stopper 12, and a frangible neck 13 having its lower end materially reduced at its point of connection or formation with the main 45 and integral neck 11, this point being indicated by the numeral 14. On both sides of the reduced portion of the neck there are provided circular ribs 15 and 16, the rib 15 being formed with the neck 11 and the rib 50 16 being formed at the lower end of the neck 13 and adjacent to the reduced portion thereof. An auxiliary stopper 17 is adapted to lie within the frangible neck 13 and above the auxiliary stopper the remainder of the

frangible neck is filled with a sealing substance 18 preferably in the nature of concrete or the like, an elliptical baffle 19 in the nature of a flat plate being arranged to be embedded in the sealing substance 18 and extending at an angle to the vertical plane 55 of the neck, as shown, so as to prevent the insertion of an instrument into the lower portion of the neck 13 in the event that the concrete or sealing substance 18 is removed from the neck. 60

The stoppers 12 and 17 are preferably connected by a thin thread or other connecting member 20, as shown, with the said ribs extending transversely to the point of breaking of the frangible neck 13 with respect to 70 the neck 11. After the bottle has been filled with the desired fluid the stopper 12 is arranged in position as shown, the inner face of the neck 11 being preferably tapered to 75 accommodate the stopper and which is also tapered, it being readily understood that the stopper can be sufficiently compressed to be forced through the neck 13 and into the neck 11. The auxiliary stopper 17 is now arranged in the neck 13 and the said stoppers 80 12 and 17 are connected by the thread 20 previously carried by the stopper 12 and adapted to pass through the stopper 17 when the same is inserted in the neck. The space 85 above the stopper 13 is now filled with the sealing substance 18 and the baffle 19 is embedded in the sealing substance as shown. In order to hold the sealing substance rigidly within the neck 13 a circular recess 21 is 90 formed in the inner face of the upper portion of the neck 13 and adapted to be filled with the sealing substance, thus holding the same securely within the frangible neck.

From the foregoing description it will be apparent that the structure described is of 95 a simple and durable construction and will readily perform the object for which it is desired. When the structure has been arranged in the position shown in Fig. 1 and it is desired to remove some of the contents of 100 the bottle body it is only necessary to tap the frangible neck a slight blow, thus severing it at the point 14. The stopper 12 is now removed and it will be apparent that the contents of the bottle body can then be 105 readily poured therefrom. It will be seen that owing to the frangible neck 13 having been broken away from the body of the bot-

tle, the bottle cannot be conveniently refilled with a spurious fluid and the frangible neck replaced without detection.

Having thus described my invention, I claim:

1. In a non-refillable bottle, the combination with a bottle body including a neck, of a stopper therein, a frangible neck on the neck of the bottle body, an auxiliary stopper in the frangible neck, a sealing substance arranged above the auxiliary stopper, and a baffle embedded in the sealing substance and extending at an angle to the plane of the said bottle body and the said auxiliary neck.
- 10 2. In a non-refillable bottle, the combination with a bottle body including a neck, of

a stopper carried in the neck, a frangible neck carried by the neck of the bottle body, an auxiliary stopper in the said frangible neck, a connecting member connecting the stopper in the neck of the bottle body and the auxiliary stopper in the said frangible neck, means for hermetically sealing the said frangible neck, and an elliptical baffle carried within the said frangible neck and lying at an angle to the vertical plane thereof.

In testimony whereof I affix my signature in presence of two witnesses.

CONRAD V. O'MALLEY.
